UNITED STATES PATENT OFFICE.

HENRY W. WENDT, OF BUFFALO, NEW YORK, ASSIGNOR TO BUFFALO FORGE CO., OF BUFFALO, NEW YORK.

DESIGN FOR A BLOWER-GEAR CASING.

46,152.

Specification for Design.

Patented July 21, 1914.

Application filed February 24, 1914. Serial No. 820,765. Term of patent 14 years.

To all whom it may concern:

Be it known that I, HENRY W. WENDT, a citizen of the United States of America, residing at Buffalo, in the county of Erie and State of New York, have invented a new, original, and ornamental Design for Blower-Gear Casings, of which the following is a specification, reference being had to the accompanying drawing, forming a part thereof.

The figure is a side elevation of a blower gear casing, showing my new design.

I claim:

The ornamental design for a blower gear casing, as shown.

HENRY W. WENDT.
